UNITED STATES PATENT OFFICE

FRED W. REHER, OF WATERBURY, CONNECTICUT, ASSIGNOR TO THE CHASE COMPANIES, INCORPORATED, OF WATERBURY, CONNECTICUT, A CORPORATION

SECTIONAL DOORSILL OR THE LIKE

Application filed February 26, 1932. Serial No. 595,264.

This invention relates to an improvement in sectional structural plates, and particularly to sectional structural plates designed for use as doorsills, though available for use in 5 a variety of other situations where structural plates of similar characteristics are desirable.

Sectional doorsills and other sectional structural plates as heretofore manufactured have been open to several objections, among 10 which may be mentioned tendency to looseness between the sections, which causes cracks therebetween and occasions considerable annoyance by way of noise when such plates are tread upon or otherwise subjected to vibration or strain.

One of the main objects of my present invention is to provide, at a low cost for manufacture, a superior sectional doorsill or the like structural plate, characterized by a tight 20 interfitting of the sections to minimize cracks, noise, etc., without requiring extreme precision of manufacture or of assembly.

With the above and other objects in view as will appear from the following, my invention 25 consists in a sectional doorsill or similar sectional structural plate, having certain features of construction and combinations and arrangements of parts as will be hereinafter described and particularly recited in the 30 claims.

In the accompanying drawing:

Fig. 1 is a perspective view of one form 35 which a doorsill constructed in accordance with my invention may assume;

Fig. 2 is a broken transverse sectional view taken on the line 2—2 of Fig. 1 but on a larger scale;

Fig. 3 is a perspective view of two of the 40 plate-sections located in position for being assembled.

The particular sectional doorsill herein chosen for the illustration of my invention consists, as shown, of a laterally-tapered end-plate 10, intermediate tread-plates 11 and 12, and a laterally-tapered end-plate 13 complementing the end-plate 10 before referred to. The plates 10, 11, 12 and 13 are preferably produced by an extrusion process in indeterminate lengths, to be subsequently cut off 45 into suitable lengths as required to meet the

exigencies of a given installation. The said plates may have their respective upper surfaces shaped to provide anti-slip areas, such, for instance, as by providing alternate longitudinal ribs 14 and longitudinal grooves 15 shown in the accompanying drawing as 55 formed on the intermediate tread-plates 11 and 12.

The intermediate plate 11 as shown is provided in its upper face with a longitudinal groove or runway 16 to provide a guide for a sliding door, and is formed in its under-side with longitudinal grooves 17—17 for the purpose of lightening the plate without diminishing its depth. Similarly, the plates 10, 12 and 13 are provided in their under-faces with longitudinal grooves 18, 19 and 20 respectively, to afford the maximum lightness consistent with strength.

In the particular doorsill illustrated, the 70 right edge (as viewed in the drawing) of each of the plates 10, 11 and 12 is formed with an undercut groove 21 preferably of the so-called "dovetail" form in cross-section and extending longitudinally of each of the given plates. The left edge (as viewed in the drawing) of each of the plates 11, 12 and 13 is formed with a dovetail or equivalent interlocking rib 22 adapted to snugly fit within the undercut groove 21 of the immediately- 75 adjacent plate, as clearly shown in Fig. 1 of the drawing.

Each of the dovetail-ribs 22 is split or bifurcated by forming therein a longitudinal groove 23 preferably of V-shaped form and which results in the formation of two complementary resilient flange-like fingers 24—24 which respectively frictionally engage with the upper and lower walls of the particular dovetail-groove 21 into which the rib 80 is interfitted.

From the foregoing, it will be seen that the intermediate plates 11 and 12 are each formed at their respective opposite edges with a dovetail-rib and a dovetail-groove, though it is 85 obvious without further illustration that a given plate-section may be provided with two undercut grooves or two flaring ribs, though the arrangement shown is preferred.

The number of plates, as well as the in- 90 95 100

- dividual character of each, entering into the makeup of a doorsill or other sectional plate will vary according to the particular requirements of a given installation. For instance, 5 when a wide sill is required, additional plates may be inserted and connected together to provide the required width, and conversely, if a narrow sill is required, some or all of the intermediate plates may be omitted. If the 10 sill is designed to be used in connection with a sliding door, a section like the plate 11 shown will be employed to form a part of the complete sill-structure, so as to provide a runway 16.
- 15 The dovetail-ribs 22 of the respective sill-sections may be initially sized so as to snugly fit the complementary undercut-grooves 21 of the members with which they are to be interlocked, or they may be initially manufactured with a free fit and expanded upon the job to insure a snug interlock, to thus avoid objectionable noise incident to vibration and strain.
- 20 It will be readily appreciated that it is a difficult matter to provide plate-sections with solid ribs which will snugly fit an undercut groove without offering so much resistance to assembly as to occasion the distortion and possible mutilation of the plates in an effort 25 to drive them together. By means of my invention, I provide laterally-yielding interlocking-ribs which may be spread sufficiently to tightly engage the walls of the undercut grooves into which they are to fit, 30 without, however, occasioning a jamming action which would require the exertion of such force as would consume time and effort and might result in the damaging of the sill-sections.
- 35 40 It will be understood by those skilled in the art that my invention may assume varied physical forms without departing from my inventive concept, and I, therefore, do not limit myself to the specific embodiment herein chosen for illustration, but only as indicated in the appended claims.
- I claim:
- 45 50 1. A sectional sill or the like, including a plurality of plate-sections, one of which is provided in its edge with a longitudinal undercut groove and the adjacent plate-section of which is provided in its edge with a transversely-yielding longitudinal interlocking rib fitting into and resiliently-engaging the undercut groove in the other said plate-section.
- 55 60 2. A sectional sill or the like, including a plurality of plate-sections, one of which is provided in its edge with a longitudinal undercut groove and the adjacent plate-section of which is provided in its edge with a bifurcated longitudinal interlocking rib fitting into and resiliently-engaging the undercut groove in the other said plate-section.

3. A sectional sill or the like, including a plurality of plate-sections, one of which is provided in its edge with a longitudinal undercut groove and the adjacent plate-section of which is provided in its edge with an interlocking rib split to form complementary diverging resilient fingers fitting into and resiliently-engaging the undercut groove in the other said plate-section. 70

4. A sectional sill or the like, including a plurality of plate-sections, one of which is provided in its edge with a longitudinal dovetail groove and the adjacent plate-section of which is provided in its edge with a transversely-yielding longitudinal interlocking rib fitting into and resiliently-engaging the dovetail groove in the other said plate-section. 75

5. A sectional sill or the like, including a plurality of plate-sections, one of which is provided in its edge with a longitudinal dovetail groove and the adjacent plate-section of which is provided in its edge with a bifurcated longitudinal interlocking rib fitting into and resiliently-engaging the dovetail groove in the other said plate-section. 80

6. A sectional sill or the like, including a plurality of plate-sections, one of which is provided in its edge with a longitudinal dovetail groove and the adjacent plate-section of which is provided in its edge with an interlocking rib split to form complementary diverging resilient fingers fitting into and resiliently-engaging the dovetail groove in the other said plate-section. 85

7. A sectional sill or the like, including a plurality of plate-sections, one of which is provided in its edge with a longitudinal dovetail groove and the adjacent plate-section of which is provided in its edge with an interlocking dovetail rib bifurcated to form two continuous diverging laterally-yielding fingers fitting into and resiliently-engaging the dovetail groove in the other said plate-section. 90

8. A structural plate for doorsills or the like, having a transversely-yielding interlocking rib in one of its edges. 105

9. A structural plate for doorsills or the like, having a transversely-yielding interlocking rib in one of its edges and having a complementary undercut groove upon its opposite edge, the said groove being shaped to receive an interlocking rib of the same character as the rib referred to. 110

10. A structural plate for doorsills or the like, having one of its edges provided with an interlocking rib longitudinally split to form complementary resilient fingers. 115

11. A structural plate for doorsills or the like, having one of its edges provided with an interlocking rib longitudinally split to form complementary diverging resilient fingers and having a complementary undercut groove upon its opposite edge, the said groove 120

130

being shaped to receive an interlocking rib of the same character as the rib referred to.

12. A structural plate for doorsills or the like, having an interlocking rib formed with a V-shaped groove dividing the same into two continuous resilient flanges diverging from each other and yieldable toward each other.

In testimony whereof, I have signed this
10 specification.
